UNITED STATES PATENT OFFICE.

JOSEPH A. CRANE, OF ROCHESTER, NEW YORK.

MACHINE FOR MAKING CORE-BOX SECTIONS.

SPECIFICATION forming part of Letters Patent No. 584,854, dated June 22, 1897.

Application filed October 14, 1895. Serial No. 565,540. (No model.)

To all whom it may concern:

Be it known that I, JOSEPH A. CRANE, of Rochester, in the county of Monroe, in the State of New York, have invented new and useful Improvements in Machines for Making Core-Box Sections, of which the following, taken in connection with the accompanying drawings, is a full, clear, and exact description.

My invention relates to improvements in machines for forming core-box sections, and has for its object the production of a simple and practical device which is easily operated and is durable and efficient in use; and to this end it consists, essentially, in the general construction and arrangement of the component parts of the machine, all as hereinafter more particularly described, and pointed out in the claims.

In describing this invention reference is had to the accompanying drawings, forming a part of this specification, in which like letters indicate corresponding parts in all the views.

Figure 1 is a top plan view, partly broken away, of my invention, illustrating the general construction and arrangement of its component parts, a core-box section being illustrated by full and dotted lines in operative position upon the table or support and the movable plates for opening and closing the apertures in the table or support being shown as withdrawn from their normal position. Fig. 2 is a longitudinal vertical section, partly in elevation, taken on line 2-2, Fig. 1, the table or support being indicated by full lines as depressed and by dotted lines as in its elevated and intermediate positions and a gage being operatively mounted upon the shaft for effecting adjustment of the knives of the cutter. Fig. 3 is a top plan view, partly in section, of my improved machine, the table or support being removed. Fig. 4 is an enlarged vertical detail section of a portion of the main division of the rotary shaft, its detachable division, the cutters mounted on the shaft, the adjacent portions of the supporting-frame for the shaft, the table or support, and the adjuster and movable stop for the table or support, a grooved core-box section being indicated as mounted upon the table or support, which is shown as elevated above its position

assumed when the cutters are engaged with the inner face of the grooves of said core-box section. Fig. 5 is a vertical section taken on line 5-5, Fig. 4, representing the cutter on the main division of the shaft, dotted circular lines being drawn concentric with the outer edges of the knives of the cutter. Fig. 6 is a longitudinal vertical section of a slightly modified form of my invention provided with a different construction of cutter. Fig. 7 is an elevation, partly in section, of the supplemental or detachable division of the rotary shaft for the modified form of my improved machine illustrated at Fig. 6; and Fig. 8 is a longitudinal vertical section of a portion of a core-box section and a series of modified constructions of knives for forming the grooves with which said core-box section is provided.

It is well known that the grooves of core-box sections must be formed with great accuracy and that expensive templets and considerable hand-work is at present necessitated in their manufacture, thus greatly adding to their expense and requiring considerable time in their production. My invention is therefore designed to manufacture core-box sections accurately, quickly, and economically; and it consists, essentially, of a rotary shaft B, provided with a cutter, and a table or support D for the core-box section, arranged normally above the shaft B and tilting toward and away from the same in a vertical plane substantially parallel with the axis of said shaft and provided with a slot lined with the shaft.

The frame A is of any desirable form, size, and construction, and is here illustrated as consisting of an upper plate a, uprights a'a', and bars a'a', between the lower ends of the uprights a'a'. The main division B of the rotary shaft is journaled in bearings a', projecting above the plate a of the frame A, and is provided with a pulley or other power-transmitting wheel b. The lower portions of the uprights a'a' are provided with bearings a'a', and journaled therein is a driving-shaft C, provided with a pulley or power-transmitting wheel c, connected by a suitable belt p' to the wheel b for revolving the shaft-division B. The shaft C may be driven by any suitable power-transmitting mechanism and is

illustrated as provided with tight and loose pulleys C' , which are engaged by a suitable belt. (Not here illustrated.)

The table or support D , which, as previously stated, is arranged normally above the rotary shaft, is formed of any desirable size and construction suitable for permitting and facilitating the operation of my machine. The upper face of the table or support D is substantially flat and forms a bearing for the core-box section, which is preferably movable lengthwise thereof in a plane substantially parallel with the cutter-shaft.

At Fig. 4 I have shown a core-box section formed by my machine as mounted upon the table or support D , which is shown as somewhat elevated above its position assumed when the core-box section is engaged by the cutter-knives. At Fig. 1 I have shown a similar core-box section, partly in section and partly by dotted lines. The table or support D tilts toward and away from the cutter-shaft in a plane substantially parallel with the axis of said shaft, as previously stated and as indicated by line x , Fig. 1, and said table or support is provided with a longitudinal slot D' , which is alined with said shaft, is formed of greater width than its diameter, and is provided at one end with an enlargement d' , registered with the pulley b and formed of greater width than the diameter thereof.

The table or support D is raised and lowered and held in its adjusted position by any suitable means, and I have here shown the table or support as mounted on a pivot e , arranged at substantially right angles with the axis of the cutter-shaft, and as connected at one side of the pivot to a suitable adjuster. The pivot e is preferably supported by a frame or supporting piece E , connected to the frame A by a pivot e' , also arranged at substantially right angles with the axis of the cutter-shaft. The frame or supporting piece E is preferably arranged beneath one end of the table or support A , and one side thereof receives the pivot e' and is interposed between arms a' , projecting from the adjacent upright a' . The opposite side of the frame or supporting piece E is preferably provided with projecting arms e'' for receiving the pivot e , which is usually arranged in arms d , depending from the table or support D , and said bearing is held in its adjusted position by any suitable means, as bolts e^3 , secured to the arms a' and passed through slots e^4 in the arms e'' . The adjuster for the table or support D is here shown as consisting of a screw F , rectilinearly guided in a bearing A' , projecting from one of the uprights a' and provided at its lower end with a handpiece or engaging portion f . The opposite end of the adjuster F is provided with a ball-shaped extremity f' , arranged in a socket g , formed in a yoke or arm G , depending from the adjacent extremity of the table or support D .

The table or support D is normally ele-

vated, so that its upper or bearing face is arranged in substantially the same horizontal plane as the top or uppermost face of the cutter of greatest diameter, whereupon the block from which the core-box section is to be formed is placed upon the table or support against the gage thereon, presently described. The block is then reciprocated along the gage upon the bearing-face of the table or support, which may then be gradually lowered until its upper or bearing face is substantially alined with the horizontal plane of the axis of the cutter-shaft. It will be understood, however, that when the core-box section is of sufficient length, so that when reciprocated its end would engage the pulley b and the bearing a^3 adjacent to said pulley if said parts projected above the bearing-face of the table or support D , then the right-hand end of the table or support, preferably adjusted by the frame or support E , is not sufficiently depressed, if adjusted at all, to permit said pulley b and bearing a^3 to project above said bearing-face, and the necessary adjustment of the table or support is effected solely by the adjuster F .

It is extremely desirable to limit the downward movement of the free extremity of the table or support D , and consequently my machine is provided with a stop G' , consisting, preferably, of a screw guided in the bearing A' and having one extremity provided with a handpiece or engaging portion g' and its opposite extremity projecting above a top face of the bearing A' for engaging the under face of the yoke or arm G . This stop is extremely simple and practical, but it is evident that other well-known forms of stops may be used, if desired.

The table or support D preferably consists of an upper facing d^2 , of wood or other suitable material, and a lower plate d^3 , provided with central openings d^4 d^5 therein for decreasing its weight. The facing d^2 is provided with apertures or cut-outs d^6 d^7 therethrough alined with the cutters, presently described, and these apertures are opened and closed by movable plates d^8 d^9 , formed of desirable width and length and provided with longitudinal shoulders d^{10} , engaging shoulders d^{11} along the edges of the apertures d^6 d^7 .

A suitable gage H is adjustably mounted upon the top face of the table or support D and is arranged at one side of the slot D' and substantially parallel with the cutter-shaft for engaging the adjacent side of the core-box section and guiding the same in its reciprocal movement. Said gage is provided with rearwardly-extending slotted arms h , secured to the table by clamps h' h'' , here illustrated as thumb-screws. Suitable stops I are movable lengthwise of the gage H and project laterally beyond the bearing-face of said gage for engaging the ends of the core-box section and limiting its movement lengthwise of the gage H . Suitable clamps, as

thumb-screws i hold the stops I in their designed position and permit ready adjustment thereof.

The shaft-division B is provided with a main cutter J , alined with the aperture d^2 in the table or support D , and, as preferably constructed, this cutter consists of a frame or hub j and knives j' , secured to the frame. The frame j is provided with a screw-threaded 10 socket j^2 for engaging a screw-threaded portion b' of the shaft-division B , and is preferably formed with radial guides j^3 , of suitable length for receiving the knives j' , which are adjustably held in operative position by suitable clamps or screws j^4 . I preferably use a series of knives having their cutting ends j^5 unequally separated from the axis of the cutter and arranged in planes at one side of each other, and it is evident that the guides 20 j^3 of the frame j for receiving the shanks of the knives are similarly arranged. The cutter J is removably secured to the shaft-division B and may be replaced with a cutter of different construction suitable for producing 25 a groove of different form in the core-box section.

The rotary shaft carrying the cutters of my machine is preferably provided with a detachable division B' for supporting an additional cutter J' , alined with the aperture d^2 in the facing d^2 of the table D . This latter cutter J' is only used, however, when the former cutter J is inadequate for forming a portion of the groove of the desired contour and depth. 30 One end b^2 of the detachable shaft-division B' is screw-threaded and engaged with the outer end of the socket j^2 of the cutter J and the other end b^3 of said shaft-division is screw-threaded and engaged with one end of a similarly-formed socket j^{10} in the frame or hub J^{10} of the cutter J' . The opposite end of the cutter-frame is journaled in an upright arm or movable bearing A^2 , removably secured by a suitable clamp or screw A^3 to the projecting 45 end of a support A^4 . The opposite end of the support A^4 is journaled in an aperture A^5 , formed in the free end of the bearing A' , which is preferably extended upwardly above the remaining portion of said bearing. The frame 50 J^{10} of the additional cutter J' is provided with separated guides j^{11} for receiving the knives, which are formed with intermediate cutting portions j^{12} and substantially parallel extremities movable in the guides j^{11} and held 55 in operative position by a suitable clamp or screw j^{13} .

The cutters upon the stationary and detachable shaft-divisions B B' are here shown as of different construction and as provided 60 with cutting-faces unequally separated from the axis of the shaft for forming grooves of different diameter and contour in the core-box section. It is evident, however, that as these cutters are detachable they may be replaced with others for varying the diameter and contour of the grooves of the core-box 65 section produced by my machine, and that, if

desired, the dissimilar cutting-faces of two cutters of equal diameter may project uniformly beyond the axis of the shaft carrying the same for forming a single groove in the core-box section of the same diameter having its opposite ends of different contour. It is also evident that when only the cutter J is required the detachable shaft-division B' may be removed and the upright arm or bearing A^2 permitted to assume its position indicated by dotted lines at Fig. 4 with its normal upper end depressed beneath the free extremity of its support A^4 .

My improved machine is frequently constructed so that a single cutter only can be used at a time, and, as illustrated at Figs. 6 and 7, it consists of a frame A^{10} , main and detachable shaft-divisions B^{10} B^{11} , a table or support D^{10} , a bearing A^{11} , an upright A^{12} , and a support A^{13} , similar to the like parts A B B' D A' A^2 A^4 of the construction of my machine previously described. A yoke or arm G^{10} , arranged at one side of the longitudinal plane of the shaft-division B^{10} , and provided with a socket g^{10} for an adjuster F^{10} , is secured to the under side of the table or support D^{10} and is formed considerably shorter than the like part G of the previously-described construction of my invention.

I have illustrated a slightly-modified form of cutter J^{20} as secured to the shaft division B^{10} , but it is evident that any other suitable cutter may be used with this construction of my machine. The cutter here illustrated consists of a frame j^{20} and knives j^{21} of similar construction to the knives j^{12} , previously described, having their opposite ends secured by bolts j^{22} to the frame j^{20} . When desired to use the detachable shaft-division B^{11} , Fig. 7, which is of the same construction as the previously-described shaft-division B' , the cutter J^{20} is removed and said shaft-section B^{10} is secured in operative position and provided with a suitable cutter. (Not illustrated.)

At Fig. 8 I have shown modified forms of cutting-knives j^{20} j^{10} j^{50} j^{60} as operatively engaged with a core-box section J^{20} for indicating the different contour of the grooves produced by said knives, and it will be understood that cutters provided with any of these knives may be used with my invention.

In the operation of my invention the table or support is arranged with its upper face in substantially the same horizontal plane as the top or uppermost face of the cutter of greatest diameter, and a block from which a core-box section is to be formed is arranged upon the upper or bearing face of the table or support against the gage on said face. The block is then reciprocally moved lengthwise of said face between the shoulders on the gage and across the cutter. The table or support is lowered gradually during the movement of the block, and the depth of the groove therein is constantly increased until the core-box section is provided with a groove of the desired depth. If the groove in the core-box

section is of less diameter than the pulley *b* on the cutter-shaft, the adjacent right-hand end of the table or support is not lowered beneath its position, as seen at Fig. 2, and it will be readily understood that the block from which the core-box section is being formed can be moved lengthwise of the table without engaging the pulley; and when the core-box section is shorter than the distance between said cutter and pulley and is provided with an open-ended groove both ends of the table may be lowered into alignment with the axis of the shaft, provided that the groove in said section is of greater diameter than the box *a*, adjacent to the cutter. On the contrary, if the groove in the core-box section is of less diameter than said box it will be formed by the supplemental cutter and the left-hand end of the table will be lowered but slightly more than seen at Fig. 2, and if said groove is formed with closed ends it will be necessary to incline the top face of the table or support so that the end of the core-box section nearest the pulley *b* will not engage and ride upon the shaft and its box at the right-hand end of the cutter.

In the operation of my machine the cutter does not project at right angles from the top face of the table or support when inclined, as at Fig. 2, and consequently the groove formed thereby is not exactly semicircular; but, even after most careful tests, it has been demonstrated that the variation cannot be perceived by the eye of a skilled mechanic and can hardly be noticed even with the most careful manipulation of a perfectly true templet. This variation is therefore immaterial, and if the grooves are not exactly semicircular they are substantially so.

The operation of my improved machine will now be readily understood upon reference to the foregoing description and the accompanying drawings, and as it is obvious that the exact detail construction and arrangement of its component parts may be considerably varied without departing from the spirit of my invention I do not herein specifically limit myself to such exact detail construction and arrangement.

Having thus fully described my invention, what I claim as new, and desire to secure by Letters Patent, is—

1. In a machine for forming core-box sections, the combination of a rotary shaft provided with a cutter, a table or support for the core-box section arranged normally above the shaft and tilting toward and away from the same in a vertical plane substantially parallel with the axis of said shaft, and provided with a slot arranged parallel with the shaft and aligned therewith, substantially as and for the purpose described.

2. In a machine for forming core-box sections, the combination of a rotary shaft provided with a cutter, a table or support for the core-box section arranged normally above the shaft and tilting toward and away from the

same in a vertical plane substantially parallel with the axis of said shaft, and provided with a slot arranged parallel with the shaft and aligned therewith, a frame for supporting the table or support mounted on a pivot arranged at substantially right angles with the axis of the shaft, and means for holding the table or support in its adjusted position, substantially as and for the purpose specified.

3. In a machine for forming core-box sections, the combination of a table or support having one extremity pivoted and provided with a substantially flat bearing-face arranged at substantially right angles with the axis of said pivot for supporting a core-box section movable lengthwise thereof, said table or support being formed with a lengthwise slot in the bearing-face, a rotary shaft arranged normally beneath the table or support in alignment with said slot and provided with a cutter projecting above said face for forming a lengthwise groove in the core-box section as it moves along the table, and an adjuster for raising and lowering the opposite extremity of the table or support, substantially as and for the purpose described.

4. In a machine for forming core-box sections, the combination of a table or support having one extremity pivoted and its opposite extremity provided with a socket in its lower face, said table or support being provided with a substantially flat bearing-face arranged at substantially right angles with the axis of said pivot for supporting a core-box section movable lengthwise thereof and being formed with a lengthwise slot in the bearing-face, a rotary shaft arranged normally beneath the table or support in alignment with said slot and provided with a cutter projecting above said face for forming a lengthwise groove in the core-box section as it moves along the table, and an adjuster or screw having one end provided with a ball-shaped extremity arranged in said socket, substantially as and for the purpose described.

5. In a machine for forming core-box sections, the combination of a table or support having one extremity pivoted and provided with a substantially flat bearing-face arranged at substantially right angles with the axis of said pivot for supporting a core-box section movable lengthwise thereof, said table or support being formed with a lengthwise slot in the bearing-face, a rotary shaft arranged normally beneath the table or support in alignment with said slot and provided with a cutter projecting above said face for forming a lengthwise groove in the core-box section as it moves along the table, an adjuster for raising and lowering the opposite extremity of the table or support, and a movable stop for limiting the downward movement of said table or support, substantially as and for the purpose specified.

6. In a machine for forming core-box sections, the combination of a table or support

provided with a substantially flat bearing-face for supporting a core-box section movable lengthwise thereof; a rotary shaft extending lengthwise of the bearing-face and provided with a cutter projecting above said face for forming a lengthwise groove in the core-box section as it moves along the table, a bearing having one side pivoted and its opposite side pivoted to an extremity of the table or support by a pivot having its axis arranged at substantially right angles with the rotary shaft, and an adjuster for raising and lowering the opposite extremity of the table or support, substantially as described.

15 7. In a machine for forming core-box sections, the combination of a table or support provided with a substantially flat bearing-face for supporting a core-box section movable lengthwise thereof and formed with a lengthwise slot in said face, a rotary shaft arranged normally beneath the table or support in alignment with said slot and provided with

a cutter projecting above said face for forming a lengthwise groove in the core-box section as it moves along the table, a bearing 25 having one side pivoted and its opposite side pivoted to an extremity of the table or support by a pivot having its axis arranged at substantially right angles with the bearing-face and the rotary shaft, a clamp for holding the 30 bearing in its adjusted position, and an adjuster for raising and lowering the opposite extremity of the table or support, substantially as set forth.

In testimony whereof I have hereunto 35 signed my name, in the presence of two attesting witnesses, at Rochester, in the county of Monroe, in the State of New York, this 3d day of October, 1895.

JOSEPH A. CRANE.
